UNITED STATES PATENT OFFICE.

JOSEPH GAGLIANO, OF NEW YORK, N. Y.

NON-REFILLABLE CIGAR-BOX.

1,086,154.

Specification of Letters Patent. Patented Feb. 3, 1914.

Application filed January 15, 1913. Serial No. 742,210.

To all whom it may concern:

Be it known that I, JOSEPH GAGLIANO, a subject of the King of Italy, and a resident of the city of New York, Astoria, borough 5 of Queens, in the county of Queens and State of New York, have invented a new and Improved Non-Refillable Cigar-Box, of which the following is a full, clear, and exact description.

10 This invention relates to tobacco and has particular reference to means for handling or dispensing the better grades of cigars, cigarettes or the like.

15 Among the objects of this invention is to provide a means whereby cigars may be handled in bulk in such form that the individual cigars cannot be touched or handled and hence are kept in a perfectly clean and sanitary condition.

20 Another object of the invention is to pack cigars in such a manner as to make it an impossibility for the container to be tampered with in such a manner as to permit goods of an inferior grade or quality from 25 being dispensed therefrom.

A still further object of the invention is to provide a box or casing for cigars or other breakable objects which will provide the maximum physical protection thereto.

30 The foregoing and other objects of the invention will hereinafter be more fully described and claimed and illustrated in the drawings forming a part of this specification in which like characters of reference indicate corresponding parts in all the views, 35 and in which—

Figure 1 is a perspective view of a box indicating the nature of this invention, a portion of the lid being broken away; Fig. 40 2 is a similar view indicating the nature of the box before it is sealed; and Fig. 3 is a vertical longitudinal section indicating the relation of the cigars to the several compartments and the manner of ejecting the 45 cigars therefrom.

A box or container made in accordance with this invention may be of any suitable size or dimensions with respect to the character of the individual articles contained 50 therein and dispensed therefrom. The box may be made of any suitable materials and the relative proportions of the various parts may be varied in design according to the nature of the material or the particular 55 uses to which the device may be put, without departing from the spirit of the invention

hereinafter claimed. I wish it to be understood also that while I use, for convenience of description throughout this specification, the term "cigars," such term is to be considered generic in scope and not in a limiting sense. 60

The box illustrated comprises a body 10 having any suitable number or arrangement of preferably parallel compartments 11 extending from the front 12 to the rear 13 of the box. The length of the box in this respect should preferably be substantially equal to the length of the cigars to be contained in the several compartments. It 65 should be noted, that each cigar is intended to occupy its individual compartment and not come in contact with any other cigar, and also that when one or more of the cigars are removed from the box, the remaining 70 cigars will not be disturbed by such removal, nor will they be accessible except by the means provided for such purpose.

As shown especially in Fig. 2, the front end of the box 12 is so arranged that the cigars 80 may be slipped into their several compartments during the ordinary filling operation, and thereafter such end of the box is closed and sealed in a permanent manner. The cover or closure for such front end consists 85 of a holder 15 having as many openings 16 as there are compartments 11, such openings alining with the respective compartments. The holder is shown comprising a pair of plates 17 and 18 of substantially the 90 size of the end of the box 12, and secured firmly between such plates is a strip of thin paper 19 which may be of any suitable nature with respect to transparency, strength and imperviousness. Said strip 19 will be 95 understood to be held in fixed position as a whole by and between the plates 17 and 18, but it may be broken or ruptured at any one or more of the openings 16 for the purpose of ejecting cigars from the box, the paper 100 guarding all of the other openings remaining unbroken under normal conditions. As above intimated, the protecting strip 19 may be of such nature as to permit moisture to pass therethrough, if desired, for the purpose of maintaining the cigars in proper 105 sealable condition.

The holder 15 is preferably made in such a manner and connected to the box so as to be carried thereby in the position indicated 110 in Fig. 2 until the box is filled, such connection being through a hinged portion 20

along the lower edge. After the box is filled, the holder will be swung into the position shown in Figs. 1 and 3, the gummed flaps 21 and 22 being secured to the walls of the 5 box and there sealed by means of a Government stamp or the like indicated at 23 in a manner well understood in this art. The other or rear end of the box is constructed 10 in a manner somewhat similar to the front end, the same including a holder 15 comprising a pair of plates 17 and 18, whereby the strip 19 of breakable material is permanently secured to the rear end of the box, 15 preferably by the box maker, it being understood that the closure for the rear end of the box is never disturbed after the box is made until the cigars are dispensed or used 20 from the box individually. The openings at the rear end are substantially the same as those already described and register with the several compartments 11. 25 With the device made as herein set forth and filled as illustrated, any authorized person may remove a cigar C therefrom by forcing through one of the openings 16, breaking the strip 19 opposite one end of the cigar and causing the cigar to break its way through the opposite end of the same compartment far enough for it to be grasped 30 at its opposite end and then withdrawn in an obvious manner. It will, of course, be understood that this manner of ejecting a cigar will not disturb any other cigar and hence none of the cigars are touched or handled 35 by either the dealer or the purchaser except those which are bought and ejected by the purchaser. The customer who is familiar with the merits of this box will, of course,

not purchase a cigar which might be found in a compartment 11, the seals 19 of which are broken. He therefore is always assured when he takes a cigar from the box that it is one which has not been contaminated by contact with any person's hands or otherwise. The structure of the box, furthermore, is that the compartments which have been emptied in the manner herein set forth cannot be refilled and resealed without detection. This fact makes it impossible for an unscrupulous dealer to violate the law 50 by supplying cigars to an empty or partially emptied box.

Having thus described my invention, I claim as new and desire to secure by Letters Patent:—

The herein described cigar box comprising a series of individual cigar compartments and closures for the opposite ends of the box, the closure at one end including a holder comprising a pair of plates both having openings of a size and form conforming to the aforesaid compartments and alining therewith, a breakable strip held between said plates and spanning said openings and normally sealing the individual compartments, and means securing the holder firmly and positively to the end of the box, substantially as set forth.

In testimony whereof I have signed my name to this specification in the presence 70 of two subscribing witnesses.

JOSEPH GAGLIANO.
